(57) **CLAIM**

The ornamental design for a display screen with transitional icon, as shown and described.

DESCRIPTION

FIG. 1 is a front view of the first image of a display screen with transitional icon;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof; and,

FIG. 7 is a front view of a seventh image thereof.

The outer broken line showing a portion of a display screen is for the purpose of illustrating a portion of the article and forms no part of the claimed design.

The appearance of the transitional image sequentially transitions between the images shown in FIG. 1-7. The process or period in which one image transitions to another image forms no part of the claimed design.

1 Claim, 7 Drawing Sheets
